UNITED STATES PATENT OFFICE

152,318

DESIGN FOR A HAND OPERATED RUG HOOKER

Joseph Blumfield, Los Angeles, Calif.

Application June 16, 1947, Serial No. 139,717

Term of patent 7 years

(Cl. D3—19)

To all whom it may concern:

Be it known that I, Joseph Blumfield, a citizen of the United States of America and a resident of the city of Los Angeles, in the county of Los Angeles and the State of California, have invented a new, original, and ornamental Design for a Hand Operated Rug Hooker, of which the following is a specification, reference being had to the accompanying drawing, forming part thereof.

Fig. 1 is a side view of the hand operated rug hooker, showing my new design;

Fig. 2 is a top view of the hand operated rug hooker;

Fig. 3 is a view taken from the right side of the hand operated rug hooker as shown in Fig. 1; and

Fig. 4 is a view taken from the left side thereof as shown in Fig. 1.

I claim:

The ornamental design for a hand operated rug hooker, substantially as shown.

JOSEPH BLUMFIELD.
